UNITED STATES PATENT OFFICE.

JAMES ALEXANDER FLANAGAN, OF TORONTO, ONTARIO, CANADA.

STITCH-FORMING MECHANISM FOR SEWING-MACHINES.

1,387,144.

Specification of Letters Patent.

Patented Aug. 9, 1921.

Application filed February 7, 1920, Serial No. 357,017. Renewed June 1, 1921. Serial No. 474,303.

To all whom it may concern:

Be it known that I, JAMES ALEXANDER FLANAGAN, a British subject, residing at the city of Toronto, in the county of York and Province of Ontario, Dominion of Canada, have invented certain new and useful Improvements in Stitch-Forming Mechanism for Sewing-Machines; and I hereby declare the following is a full, clear, and exact description of the same.

This invention relates to a stitch forming mechanism for sewing machines comprising a stationary thread case having a segmental peripheral flange with a loop holder at one extremity, and a loop taker formed with a thread case cavity, in which the thread case is journaled, and consisting of an assembly plate having a segmental cylindrical flange on its inner face formed with a peripheral shoulder, a cylindrical body member mounted on the cylindrical flange having a channel to receive the peripheral shoulder, and a segmental frusto-conical loop deflector formed at its forward end with a single beak arranged obliquely to the periphery of the thread case, and moving in rear of the needle path, for entering the loop, drawing it through the needle eye, and passing the needle side of the loop around the back of the thread case, the beak having a thread race extending from its heel to the deflector for directing the work side of the loop across the frusto-conical surface to the front side of the deflector and imparting the twist to the loop as it moves across the front of the thread case, and an internal annular flange within the deflector opposed to the flange of the assembly plate and forming with it a raceway for the peripheral flange of the thread case.

For an understanding of the invention reference is to be had to the following description and accompanying drawings, in which:

45 Figure 1, is a side view of the stitch forming mechanism showing the position of the parts when the beak of the loop taker is about to enter the loop,

Fig. 2, is an end view of the same showing the position of the parts when the beak has entered the loop,

Fig. 3, is an end view of the stitch forming mechanism showing the position of the parts when the loop holding member is about to engage one side of the loop,

Fig. 3^a, is a side view showing the parts in the same position as in Fig. 3,

Fig. 4, is an end view of the stitch forming mechanism showing the position of the parts when the loop holding member has 60 entered the loop and the loop taker is about to pass the needle side of the loop behind the thread case.

Fig. 4^a, is a side view showing the parts of the stitch forming mechanism in the 65 same position as in Fig. 4,

Fig. 5, is an end view of the parts showing the loop taker passing the work side of the loop across the front of the thread case,

Fig. 6, is a similar view to Fig. 5, showing the delivery of the loop for the take up,

Fig. 7, is a sectional view of the loop taker,

Fig. 8, is an end view of the loop holding member,

Fig. 9, is a plan view of the loop holding member,

Fig. 10, is an end view of the thread case,

Fig. 11, is a top plan view of the thread case,

Fig. 12, is an elevational view of the thread case,

Fig. 13, is a sectional view showing the assembly of the bobbin and the thread case, the latch in this case being released from the 85 axial pin,

Fig. 14, is a similar view to Fig. 13, showing the latch engaged with the axial pin and released from the bobbin,

Fig. 15, is a detail view of the latch,

Fig. 16, is a sectional detail view of the assembly plate,

Fig. 17, is a sectional detail view of the assembly plate taken at right angles to Fig. 16, and

Fig. 18, is a diagrammatic view of a twisted lock stitch.

Like characters of reference refer to like parts throughout the specification and drawings.

Incorporated in the construction of the stitch forming mechanism is a segmental cylindrical assembly member, comprising a circular assembly plate *a*, having a central boss *b* projecting beyond its rear face to receive the looper shaft, the peripheral surface of the boss having a cam *c*, which imparts a rise and fall movement to the feed dog.

The inner side face of the assembly plate 110

a has a segmental flange *d* concentric with its axis, the space *d'*, between the ends of the flange being approximately equal to one-third of the circumference of its circle to 5 provide a sufficient clearance for the reciprocation of the needle.

The outer diameter of the segmental flange *d*, as shown in Fig. 17, is slightly less than the diameter of the assembly plate, to 10 form with it a peripheral shoulder *e*; and in the flange *d* are diametrically opposed screw threaded holes *f*.

The loop taker comprises a cylindrical body section or ring *g*, which snugly fits 15 on the segmental flange when assembled with the plate *a*, the inner surface of the ring having a circular groove *h*, adjacent to its rear edge to receive the peripheral shoulder *e*. In the ring *g* are clearance 20 holes *g'* alined with the screw threaded holes *f* and passing through the clearance holes *g'*, and entering the screw threaded holes *f* are machine screws *i*, securing the plate *a*, and the loop taker together. The 25 periphery of the ring *g* is cut away for about one-third of its circumference, as shown at *j*, and this cut away part is alined with space *d'* in the segmental flange *d* to also provide a clearance for the needle.

30 Integrally formed with the ring *g*, at one side of the cut away part *j*, is the beak *l*, which moves in a circular path in rear of and adjacent to the vertical path of the needle *k*.

35 The beak, as shown in Fig. 2, is located at the right of the cut away part *j* with its point *m* directed to the left. The rear side *l'* of the beak is oblique to the face of the ring *g* to form with its peripheral surface, 40 a heel *o*. The heel of the beak is rounded and the peripheral surface of the ring is beveled from the heel of the beak toward the right to form a thread race *o'* for the work side of the loop. The front side *l''* of the 45 beak recedes slightly from the point *m*, in the direction of the ring *g* to provide a clearance for the movement of the needle when the beak has seized the loop and is carrying it forward for the formation of the stitch, 50 and the inner face of the beak has a convex part *r* slightly behind the point *m* to press the bottom *p'* of the loop within the circle of the stationary hook *s* and thus insure the stationary hook engaging the bottom *p* of 55 the loop when the rotary loop taker carries the loop to it.

60 Integrally formed with the front face of the ring *g* is a segmental frusto conical loop deflector *t* extending from the rear of the beak *l* partially around the ring to the opposite side of the cut away part *j*. Within the bore of the ring *g* is an annular flange *u* which in conjunction with the flange *d* forms a race for the stationary hook *s*.

65 The stationary hook *s* consists of a seg-

mental flange or rib integrally formed with or secured to the peripheral surface of the cup shaped body section *v* of the thread case, and when the parts are assembled it abuts against and is contained between and maintained in position by the flanges *d* and *u*. The body section *v* is provided with an internal axial pin *v'* having a groove *v''* near its outer end to receive the latch *w* of the cap section *x* of the thread case. The rim 70 of this body section is provided with a bifurcated projecting lug, the forks *y*, *y'*, of which are separated by an intervening slot *y''* forming the path for the needle *k*.

The needle and shuttle threads for the 80 stitch pass upwardly through the slot *y''* and are maintained in position by the forks *y*, *y'*. The fork *y* as shown in Figs. 1 to 6 inclusive has an upturned end *y''*, which is engaged by a holding member *y'* conveniently secured to the bed plate of the machine to prevent the rotation of the thread case. The cap section of the thread case is also of a cup shaped formation and its cylindrical wall *z* is formed with a needle hole *z'* alined, 90 when the parts are assembled, with the slot *y''*.

The periphery of the cylindrical wall *z*, as shown in Fig. 11, is formed with a segmental rib or flange *a'*, the ends of which are separated by an intervening space *z''* to receive between them the forks *y*, *y'*, which when entered therein engage the ends of the rib or flange *a'* and hold the cap section against rotation and thus maintain it in its fixed 100 relation with the body section *v* and the other parts of the stitch forming mechanism, with the needle hole *z'* in correct alinement with the slot *y''*. The cylindrical wall *z* of the cap section fits snugly within the body 105 section *v* and is not only maintained in a fixed position with relation to the body section by the engagement of the ends of the segmental rib or flange *a'* with the forks *y*, *y'*, but is brought by this means into correct 110 relation with the body section, when being assembled, the space between the ends of the segmental rib or flange, providing a clearance sufficient only for the forks *y*, *y'*, of the lug, and the rib or flange *a'* being of such 115 depth as to engage the ends of the forks *y*, *y'*, and prevent the assembly unless this clearance comes into correct alinement with them.

When the cap section *x* is assembled with 120 the body section *v*, the edge of the cylindrical wall *z* abuts against the inner face of the side or end wall *b''* of the body section *v* and in conjunction with the body section completely incloses the bobbin *b'*, thus constituting the thread case.

The cylindrical wall *z* is provided with a slit *b''* for the bobbin thread *z''*, this slit *b''* extending obliquely in an upward direction from the inner to the outer edge of the cy- 130.

lindrical wall z . Overlying the outer upper part of the slit is the free end of the tension spring c' , the other end of the spring being suitably secured to the cap section x . In the 5 side or end wall a'' of the cap section is a thread channel c'' extending transversely across it in line with the upper end of the slit b^3 and secured to the outer or end wall a'' above the thread channel c'' is a flat plate 10 d'' , the end of which is formed with an inclined slot d^3 terminating in the thread delivery aperture d^4 . In the outer face of the end wall a'' is a slideway e' parallel with the channel c'' and movable in this slideway 15 is a slide member e'' . The slide member e'' has a lateral lug f' overlying the end of the slideway e' , and this lug is pressed by a spring f'' seated in a chamber f^3 formed in the end wall a'' , the end wall having a cut 20 away part g'' for the movement of the lug f' . The slide member e'' has a hooked shaped lug g^3 extending lengthwise of the axis of the cap section and overhanging the edge of the end wall a'' , the cylindrical 25 wall z being formed with an aperture i' for the movement of the lug g^3 and for the entry of its hook shaped end g^4 into the bobbin holding member.

Formed centrally through the slide member e'' and the end wall a'' is a bore i'' for the axial pin v' , and extending into the bore i'' from the slide member e'' is a latch w to enter the groove v'' of the pin v' when the slide member is pressed by the spring f'' . 30 Secured centrally to the end wall a'' , and extending into the cap section is an internal sleeve j'' , the bore of which is in axial alignment with the bore i'' , to inclose the inner part of the axial pin v' , and provide a journal for the bobbin b' , the outer extremity 35 of the sleeve j'' terminating at the inner face of the end wall a'' to leave that part of the axial pin v' within the bore of the slide member e'' exposed so that the latch 40 w can enter the groove v'' .

In assembling the bobbin b' in the thread case, the hub b^4 of the bobbin b' is placed upon the sleeve j'' and the outer flange b^5 of the bobbin is engaged by the hook g^4 45 of the lug g^3 , the hook shaped lug then securely holding the bobbin correctly positioned within the cap section x while the bobbin and cap section are being assembled with the body section v . In threading the 50 machine the bobbin thread z^3 is entered in the inner end of the slit b^3 and drawn through the latter, under the free end of the tension spring c' , along the thread channel c'' , under the end of the flat plate d'' , 55 through the inclined slot d^3 , to the thread aperture d^4 . The cap section x with the bobbin is then assembled in the body section v by placing the sleeve j'' on the axial pin v' with the space between the ends of 60 the segmental rib or flange a' in line with

the forks y, y' , the slide member e'' during this assembly being manually pressed to maintain the lug g^3 in engagement with the outer flange of the bobbin and securely hold it in position with the cap section, the latch 70 w then being clear of the path of the axial pin v' .

When the manual pressure on the slide member is removed the spring f'' presses it, and disengages the hook shaped lug g^3 75 from the bobbin flange and at the same time causes the latch w to enter the groove v'' of the pin v' and lock the cap section and the body section of the shuttle or thread case together. 80

In separating the cap section from the body section the slide member e'' is pressed to release the latch w from the groove v'' and bring the hook shaped lug g^3 into engagement with the outer flange of the bobbin, thereby releasing the cap section from the body section and temporarily locking the bobbin within the cap section. The cap section and bobbin can then be withdrawn 85 from the body section. 90

In Fig. 1, of the drawings the needle k is shown to be receding, and the loop m' is shown to be formed and the point m of the beak l is about to enter it.

In Fig. 2, the beak has entered the loop 95 and is about to carry it forward to the stationary hook s for the formation of the stitch.

In Fig. 3, the beak l is shown to have carried the rear side p of the loop past the 100 stationary hook s , and the bottom p' of the loop is shown to be engaged and held by the stationary hook against farther travel, until the loop is ready to be delivered for the take up. At this stage the work side p 105 of the loop is seated at the heel of the beak l which is so positioned as to be always within the plane of the rear face of the body section of the thread case during the revolution of the loop taker, and as there 110

is no contact between the thread case and the remainder of the stitch forming mechanism, other than the peripheral rib and terminating in the stationary hook within the raceway provided for it, the beak can pass 115 the needle side of the loop freely across the back of the thread case during the revolution of the loop taker. When the heel of the beak passes the stationary hook, the work side of the loop is behind the thread case, 120 and as the beak continues its rotation the thread race o' positively passes the work side of the loop on the frusto-conical surface of the loop deflector which passes the work side of the loop to the front of the 125 thread case, as shown in Fig. 5, this movement continuing until the stationary hook is exposed by the cut away part j coming into line with it for the shedding of the loop prior to the take up. 130

Having thus fully described my invention, what I claim as new and desire to secure by Letters Patent is:

1. In a sewing machine, a stitch forming mechanism comprising a stationary thread case having a peripheral loop holder, and a rotary loop taker formed with a thread case cavity in which the thread case is journaled, and with a segmental frusto-conical loop deflector, partly encircling the thread case, having at its forward end a single beak moving in rear of the needle path, for entering the loop, drawing it through the needle eye, and passing the needle side of the loop across the back of the thread case, the beak having a thread race for directing the work side of the loop on the loop deflector to be passed by it across the front face of the thread case during the revolution of the loop taker.
2. In a sewing machine, a rotary loop taker for the stitch forming mechanism comprising a segmental cylindrical assembly member, a cylindrical body member mounted thereon, a segmental frusto-conical loop deflector for the body member, and a single beak at the forward end of the deflector having a thread race to direct the work side of the loop on the frusto-conical surface of the deflector to be passed across the front face thereof during the revolution of the loop taker.
3. In a sewing machine, a stitch forming mechanism comprising a stationary thread case having a peripheral segmental flange,

in combination with a loop taker formed with a thread case cavity in which the thread case is journaled, and comprising an assembly plate having a segmental cylindrical flange, a cylindrical body member mounted on the cylindrical flange having a segmental frusto-conical loop deflector formed at its forward end with a single beak having a thread race for directing the work side of the loop on the deflector, and an internal annular flange within the deflector opposed to the flange of the assembly plate, and forming with it a raceway for the peripheral flange of the thread case.

4. In a sewing machine, a loop taker comprising a circular assembly plate having a segmental annular flange formed with a peripheral shoulder, a cylindrical body section mounted on the flange and formed with an annular channel, to receive the peripheral shoulder, and having a segmental frusto-conical loop deflector, a single beak at the forward end of the loop deflector formed with a thread race for directing the work side of the loop on the frusto-conical surface of the deflector, and an internal annular flange within the deflector opposed to the flange of the assembly plate.
